of California

Filed Feb. 19, 1965, Ser. No. 83,893

Term of patent 14 years

(Cl. D33—14)

FIGURE 1 is a perspective view of a patio table, incorporating my invention;

FIGURE 2 is a view in side elevation thereof;

FIGURE 3 is a view in top plan thereof; and

FIGURE 4 is a view in end elevation thereof.

The design is particularly characterized by the solid, slablike structure of the legs, and by the fact that the individual legs at the side of the table comprise a pair of abutting members which are arranged at a slight angle with respect to one another (see FIGURES 1 and 4). In this regard the side of the table which is hidden from view in FIGURE 1, is the same in appearance as the side shown.

I claim:

The ornamental design for a patio table, substantially as shown and described.
